UNITED STATES PATENT OFFICE.

ROBERT B. COLTRIN, OF JACKSON, MICHIGAN.

CEMENT-MIXER.

SPECIFICATION forming part of Letters Patent No. 783,103, dated February 21, 1905.

Application filed May 12, 1904. Serial No. 207,592.

To all whom it may concern:

Be it known that I, ROBERT B. COLTRIN, a citizen of the United States, residing at Jackson, in the county of Jackson and State of Michigan, have invented certain new and useful Improvements in Cement-Mixers; and I do hereby declare the following to be a full, clear, and exact description of the invention, such as will enable others skilled in the art to which it applies to make and use the same.

My invention relates to machines for mixing and incorporating the ingredients of various classes of stock—such, for example, as plastic cement, concrete, and similar compositions—and particularly to machines of this character in which the mixing is effected in a trough or receptacle by revolving blades.

The principal objects are, first, to provide an improved mixing-receptacle and co-operating mixer by which the ingredients to be incorporated are thoroughly mixed and at the same time gradually worked and conveyed from the inlet toward the discharge end of the receptacle, the latter being horizontally disposed; second, to support the receptacle so as to avoid clogging of the material or any object between the mixing-blades and the interior walls of the receptacle, and, third, to produce an efficient and convenient machine whereby the ingredients can be fed as desired into one end of the receptacle, rapidly and effectively mixed, saturated to proper consistency while mixing, and conveyed and discharged into a suitable receptacle at the opposite end or into a spreader for distributing the composition, as in laying cement and concrete.

In the accompanying drawings, which form a part of this specification, the invention is illustrated embodied in a portable cement or concrete mixer adapted for spreading or laying the material as it is produced. The invention is, however, not confined to this or any specific embodiment, but is susceptible of general utility for mixing ingredients of various kinds of stock, compositions, or products, and the illustrated machine is of course susceptible of various modifications in details of construction and arrangement. Without limiting myself, therefore, to the particular

construction illustrated the invention will first be fully described with reference to the drawings and then more particularly pointed out and defined in the annexed claims.

In said drawings, Figure 1 represents a perspective view of a mixing-machine embodying my invention. Fig. 2 is a detail perspective of the mixer, having spirally-twisted blades. Fig. 3 represents a plan of the conical receptacle in which the mixer rotates.

Referring to these drawings by specific reference-numerals, 1 represents the main supporting-frame, mounted on side wheels 2 and the front medial guide-wheel 3, with a handle or tongue 4 attached to the shaft thereof. In the central part of the frame is a longitudinally and horizontally disposed conical shell or mixing-receptacle 5 of semicircular cross-section, suspended from the upper part of the frame by rods or by chains 6, attached to apertured lugs in the sides of the receptacle. The larger end of this mixing receptacle or trough is disposed at the back of the machine and is lower than the opposite smaller end. Sand, cement, gravel, crushed stone, or ashes or other desired materials are introduced into the smaller end of the receptacle and are mixed and at the same time gradually worked or conveyed by the revolving spiral blades of the mixer toward the larger end, from which they are discharged. This mixing-receptacle may be made integrally or in parts, secured, as shown in Fig. 3, by the bolts 7 on the under side of the receptacle. The lower end, which, as aforesaid, in this case is the larger, is open and is preferably supplied with a spout 8 to conduct the mixed material to the spreader 9. The opposite end may be partially or entirely closed to prevent the loose dry cement and sand from sifting out when first exposed to the action of the agitator. By supporting or suspending the receptacle loosely, as described, it is given a slight lateral play, which prevents clogging of the material. For instance, if a stone should accidentally be admitted with the sand between the mixing-blades and sides of the receptacle the latter would move sufficiently to allow the stone to pass out instead of bending or breaking the blade, as would otherwise occur. The mixer, which revolves closely within said re-

ceptacle, is supported by a shaft 10, which passes through the frame 11 and is supported by bearings 12. The shaft is provided with a hub 13, which carries the spiral blades 14. The blades are formed of a single piece of metal, spirally twisted, and are secured to the hub by rivets 15. The blades are so arranged that they will not strike the sides of the receptacle. The mixer is supported by a shaft 16, which passes through the frame 11 and is supported by bearings 17. The shaft is provided with a hub 18, which carries the spiral blades 19. The blades are formed of a single piece of metal, spirally twisted, and are secured to the hub by rivets 20. The blades are so arranged that they will not strike the sides of the receptacle. The mixer is supported by a shaft 21, which passes through the frame 11 and is supported by bearings 22. The shaft is provided with a hub 23, which carries the spiral blades 24. The blades are formed of a single piece of metal, spirally twisted, and are secured to the hub by rivets 25. The blades are so arranged that they will not strike the sides of the receptacle. The mixer is supported by a shaft 26, which passes through the frame 11 and is supported by bearings 27. The shaft is provided with a hub 28, which carries the spiral blades 29. The blades are formed of a single piece of metal, spirally twisted, and are secured to the hub by rivets 30. The blades are so arranged that they will not strike the sides of the receptacle. The mixer is supported by a shaft 31, which passes through the frame 11 and is supported by bearings 32. The shaft is provided with a hub 33, which carries the spiral blades 34. The blades are formed of a single piece of metal, spirally twisted, and are secured to the hub by rivets 35. The blades are so arranged that they will not strike the sides of the receptacle. The mixer is supported by a shaft 36, which passes through the frame 11 and is supported by bearings 37. The shaft is provided with a hub 38, which carries the spiral blades 39. The blades are formed of a single piece of metal, spirally twisted, and are secured to the hub by rivets 40. The blades are so arranged that they will not strike the sides of the receptacle. The mixer is supported by a shaft 41, which passes through the frame 11 and is supported by bearings 42. The shaft is provided with a hub 43, which carries the spiral blades 44. The blades are formed of a single piece of metal, spirally twisted, and are secured to the hub by rivets 45. The blades are so arranged that they will not strike the sides of the receptacle. The mixer is supported by a shaft 46, which passes through the frame 11 and is supported by bearings 47. The shaft is provided with a hub 48, which carries the spiral blades 49. The blades are formed of a single piece of metal, spirally twisted, and are secured to the hub by rivets 50. The blades are so arranged that they will not strike the sides of the receptacle. The mixer is supported by a shaft 51, which passes through the frame 11 and is supported by bearings 52. The shaft is provided with a hub 53, which carries the spiral blades 54. The blades are formed of a single piece of metal, spirally twisted, and are secured to the hub by rivets 55. The blades are so arranged that they will not strike the sides of the receptacle. The mixer is supported by a shaft 56, which passes through the frame 11 and is supported by bearings 57. The shaft is provided with a hub 58, which carries the spiral blades 59. The blades are formed of a single piece of metal, spirally twisted, and are secured to the hub by rivets 60. The blades are so arranged that they will not strike the sides of the receptacle. The mixer is supported by a shaft 61, which passes through the frame 11 and is supported by bearings 62. The shaft is provided with a hub 63, which carries the spiral blades 64. The blades are formed of a single piece of metal, spirally twisted, and are secured to the hub by rivets 65. The blades are so arranged that they will not strike the sides of the receptacle. The mixer is supported by a shaft 66, which passes through the frame 11 and is supported by bearings 67. The shaft is provided with a hub 68, which carries the spiral blades 69. The blades are formed of a single piece of metal, spirally twisted, and are secured to the hub by rivets 70. The blades are so arranged that they will not strike the sides of the receptacle. The mixer is supported by a shaft 71, which passes through the frame 11 and is supported by bearings 72. The shaft is provided with a hub 73, which carries the spiral blades 74. The blades are formed of a single piece of metal, spirally twisted, and are secured to the hub by rivets 75. The blades are so arranged that they will not strike the sides of the receptacle. The mixer is supported by a shaft 76, which passes through the frame 11 and is supported by bearings 77. The shaft is provided with a hub 78, which carries the spiral blades 79. The blades are formed of a single piece of metal, spirally twisted, and are secured to the hub by rivets 80. The blades are so arranged that they will not strike the sides of the receptacle. The mixer is supported by a shaft 81, which passes through the frame 11 and is supported by bearings 82. The shaft is provided with a hub 83, which carries the spiral blades 84. The blades are formed of a single piece of metal, spirally twisted, and are secured to the hub by rivets 85. The blades are so arranged that they will not strike the sides of the receptacle. The mixer is supported by a shaft 86, which passes through the frame 11 and is supported by bearings 87. The shaft is provided with a hub 88, which carries the spiral blades 89. The blades are formed of a single piece of metal, spirally twisted, and are secured to the hub by rivets 90. The blades are so arranged that they will not strike the sides of the receptacle. The mixer is supported by a shaft 91, which passes through the frame 11 and is supported by bearings 92. The shaft is provided with a hub 93, which carries the spiral blades 94. The blades are formed of a single piece of metal, spirally twisted, and are secured to the hub by rivets 95. The blades are so arranged that they will not strike the sides of the receptacle. The mixer is supported by a shaft 96, which passes through the frame 11 and is supported by bearings 97. The shaft is provided with a hub 98, which carries the spiral blades 99. The blades are formed of a single piece of metal, spirally twisted, and are secured to the hub by rivets 100. The blades are so arranged that they will not strike the sides of the receptacle.

ceptacle 5, is of conical form to correspond with the configuration of said receptacle. As shown, it consists of a central shaft 10, opposite end plates 11 and 12 rigid therewith, 5 and longitudinal mixing-blades 13, which connect the end plates. This mixer fits rotatably within the receptacle 5, and its shaft 10 is journaled in suitable bearings at the front and rear ends of the machine. Its blades or 10 bars 13 are twisted or spiral, so that in revolving the front portions of the blades are in advance of the rear portions, each blade thus passing into the material in the receptacle progressively from its front to its rear 15 end. By virtue of the conical shape of the mixer and the twisted or spiral blades when the mixer revolves in the direction of the arrow in Fig. 2 each revolving blade in addition to its mixing function scoops or scrapes up the 20 dry mass at the smaller end of the receptacle and at the same time feeds it toward the larger end, this action being facilitated also by the rearward downward inclination of the receptacle. The blades or bars are preferably of 25 steel and have bent terminals riveted to the inner faces of the end plates 11 and 12, though they may be attached in any suitable manner. Thus it is seen that the mixer serves also as a conveyer, and as the mass approaches the 30 larger end of the receptacle it is exposed to a regulated stream of water or liquid whereby it becomes saturated to the proper consistency, the water being mixed therewith by the blades, and its immediate discharge is prevented by 35 the scooping effect of the inclined bars, and a final and thorough mixing is thereby produced.

Rigid with the mixer-shaft 10 and preferably on the outer side of the larger end plate 40 is a sprocket or pulley 14, connected in a suitable manner to the sprocket 15, whose shaft has a crank 16 or other means for rotating.

Above the mixing-receptacle are several 45 chambers or boxes adapted to hold the ingredients necessary in mixing the concrete or composition and supply the same to the mixing-chamber. In this case these boxes are shown mounted on the top of the frame. The numeral 17 denotes the water-tank, having a 50 regulating-cock 18 and conducting-pipe 19. Numerals 20 and 21 indicate sand and cement 55 boxes, both having lift-doors 22, operated by the projecting levers or handles 23, so that the amount and proportion may be properly regulated either in a continuous or intermittent stream falling into the common spout or 60 hopper 24, where they are partially mixed before reaching the mixing-tank proper. More chambers may be added, if desired, placed 65 either on top of the machine-frame or at the side or elsewhere, as desired, and provided with suitable spouts for conducting the ingredients, whether crushed stone, cinders, or what not, into the mixing-receptacle.

65 From the foregoing description the opera-

tion of the mixer is obvious. Sand and cement or other ingredients are discharged, as desired, from their respective boxes or compartments into the mixing trough or receptacle 5, where they are thoroughly mixed by the 70 action of the rotating blades and conveyed or worked gradually toward the larger end, where the water is added. After becoming saturated and worked to a proper consistency the plastic mass flows out at the spout 8 into the 75 bed or spreader 9.

If used in making concrete walks and the like, it is very convenient to have the concrete spread and deposited in an even layer at the 80 places desired, and this may be accomplished efficiently by means of my improved machine, which is pulled along to allow the composition to flow out and spread from the spreader 9.

I claim as my invention and desire to secure by Letters Patent of the United States— 85

1. In a mixing-machine of the character described, a horizontally-disposed conical trough, and a rotating mixer therein having a conical contour corresponding to the interior shape of the trough, said mixer comprising a 90 shaft with rigid end plates constituting the end walls of the trough and connected by spiral or twisted blades all disposed in the same conical surface.

2. A mixing-machine having, in combination, a frame, a horizontally-disposed receptacle suitably supported therein having its bottom downwardly inclined, said receptacle being of parti-circular cross-section; a rotary mixer working in said receptacle comprising 95 a longitudinally-disposed shaft suitably journaled in bearings in said frame, end disks or circular plates rigid on said shaft and rotatably fitted in opposite ends of said receptacle and constituting its end walls, a discharge 100 spout at the lower end of said receptacle below the disk at that end, and mixing-blades rigidly connecting said disks and coöperating with the interior of said receptacle; and means for rotating said mixer. 110

3. A mixing-machine having, in combination, a conical trough or receptacle horizontally disposed with its bottom downwardly inclined toward its large end, and a correspondingly-shaped rotary mixer working therein 115 having longitudinal spiral or twisted mixing-blades coöperating with the interior of said receptacle, whereby material introduced at the higher and smaller end of the receptacle is mixed and worked downwardly to the larger 120 discharge end.

4. A mixing-machine having, in combination, a frame, a horizontally-disposed trough or receptacle loosely suspended therefrom, and a rotary mixer therein having fixed bearings and having longitudinal mixing-blades adapted to scrape or pass closely over the interior of said receptacle. 125

5. A mixing-machine having, in combination, a horizontally-disposed conical trough or 130

receptacle with its bottom downwardly inclined from its smaller end to its larger discharge end, a rotary mixer therein comprising end disks rotating in said trough and having spiral blades rigidly connecting said disks, ingredient-chambers above said trough adapted to discharge thereinto, and a discharge-spout at the larger end of said trough.

5 6. A portable mixer comprising, in combination, a wheeled supporting-frame, a horizontally-disposed trough therein with its bottom downwardly inclined toward the back of

the machine, a rotary mixer working in said trough, ingredient-chambers above said trough adapted to discharge thereinto, and a spreader 15 located beneath the lower discharge end of the trough for receiving and spreading the admixture as the wheeled frame is moved along.

In testimony whereof I affix my signature in presence of two witnesses.

ROBERT B. COLTRIN.
